CRACKING PROCESS

Albert C. Patterson, Roselle, N. J., assignor to
 Standard Oil Development Company, a corpora-
 tion of Delaware

Application July 11, 1936, Serial No. 90,045

4 Claims. (Cl. 196—49)

This invention relates to cracking processes, especially to those processes in which two circuits are employed, one circuit being devoted, preferably, to the cracking of virgin stock, that is, stock which has not been previously cracked, and the other circuit being devoted to cycle stock, the products of the two circuits being mixed. It is not essential that one of the stock be a virgin stock so long as one stock is less refractory than

5 the other stock.

In all processes in which a virgin stock, such as a reduced crude or a virgin gas oil, is cracked, the amount of crackable material convertible into lower boiling products is limited by coke production. That is to say, the cracking conditions can be only so intense that the amount of coke formed does not plug up the system. In practice, excessive coke formation occurs before all the crackable material in the stock is converted. In the past, 10 this has resulted in a loss of cracking stock in the tar resulting from the cracking.

For many years, in the operation of two circuit systems, it has been the practice to discharge the cracked virgin stock and the cracked cycle stock into a common separator. In many instances the cracked effluent from both cycles has been joined at a point just before their entry into the separator. More often the cracked cycle stock has been introduced into the separator at a point 15 above the point of introduction of the cracked virgin stock, probably by reason of the fact that the cycle stock is usually of a lighter character.

Recently it has been proposed to introduce the cracked cycle stock into the separator at a point below the point of introduction of the cracked less refractory stock and to interpose fractionating equipment between the two points of introduction. This has resulted in a preferential stripping of good cracking stock from the cracked 20 effluent from the less refractory stock by the cracked cycle stock and the replacement of this good cracking stock in the tar by refractory constituents of substantially the same boiling point from the cracked effluent from the cycle stock.

25 In the two-circuit systems, to which the recently proposed improvement has been directed, the cracking coil for the less refractory stock is ordinarily operated at temperatures ranging from 750 to 1000° F., usually from 820 to 900° F., and the coil for the cycle stock is operated at an outlet temperature between 850 and 1050° F., usually between 900 and 975° F. The pressure on the less refractory stock coil is ordinarily between 100 and 500 lbs./sq. in., and that on the cycle stock coil is between 300 and 1000 lbs./sq. in., and that

on the separator is much lower, usually between 50 and 150 lbs./sq. in. In such operations, the amount of good cracking stock recovered from the cracked less refractory material, while it is considerably larger than the amount obtainable without the employment of the expedient of fractionation in the separator according to the recent proposal, is still limited by the formation of coke under the operating conditions in the separator. The lower the pressure in the separator, the greater will be the amount of coke formed at a given temperature.

According to the present invention, a greater recovery of cracking stock from the tar can be achieved by separately collecting from the separating zone the tar from the less refractory stock and the tar from the more refractory stock, and introducing these tars into a common evaporator operated at a lower pressure, preferably a vacuum flash tower, at different levels, the tar from the less refractory stock being introduced at a point above the point of introduction of the tar from the more refractory stock, and fractionating equipment being interposed between them. By reason of the reduced pressure in this common evaporator it is possible to operate at lower temperatures whereby the respective tars can be reduced to a lower A. P. I. gravity number without the danger of coking. This novel procedure can be applied regardless of the conditions of operation in the respective circuits, and is not restricted to circuits operated under the general conditions outlined above, which are given merely as exemplary of conventional operation. In some instances it may be preferably to operate the cycle stock circuit at a lower pressure than that maintained in the less refractory stock circuit. It is generally true, however, that the temperature in the cycle stock circuit will be higher than the temperature in the less refractory circuit.

In order that the separation of the desired overhead may be obtained from a separator operating at pressures considerably below that existing in the cracking coil, it is necessary that the tar in the bottom of the separator be cooled, usually by circulation through a cooling coil. This procedure results in a considerable loss of heat. Likewise, the amount of heat contained in the overhead is limited by the pressure in the separator. This reduces the amount of preheat which can be imparted to the charging stock which is ordinarily passed in heat exchange relation with the overhead from the separator.

According to a preferred embodiment of the present invention, the advantages of increased

preheat to the charging stock and avoidance of loss of heat by cooling the tar in the bottom of the separator, together with the advantage accruing from stripping the virgin stock by means 5 of the cycle stock, and the additional advantage of the avoidance of coke formation, are obtained by injecting both the cycle stock and the virgin stock either into individual separators maintained at the pressures held in the respective cracking 10 coils or into a common separator maintained at a high pressure and so constructed as to provide for stripping of the virgin stock by vapors of the cracked cycle stock, while keeping the tars resulting from the respective stocks separate, 15 followed by injection of the tars from the respective stocks into a common evaporator operating at lower pressure, preferably, a vacuum flash tower, the tars from the cycle stock being introduced at a point below the point of introduction 20 of a tar from the virgin stock, and fractionating equipment being interposed between the points of introduction.

Further procedural details and advantages of the process of the present invention will be apparent from the following detailed description of 25 the accompanying drawing which is a front elevation, partly in section, of a diagrammatical form of an apparatus suitable for carrying out the preferred embodiment of said process.

Referring to the drawing in detail, virgin stock, such as reduced crude or virgin gas oil, is introduced into the system through pipe 1 from which it is pumped by pump 2, through line 3, through heat exchanger 4, referred to in greater detail 30 hereinafter, to coil 5 from which it is discharged into a soaker 6, which is shown as downflow but may be upflow, and thence into the upper part of separator 7 provided with fractionating plates 8, which may be replaced by other common fractionating equipment, and with a tray 9, the purpose of which is to collect the tar from the cracked virgin stock and feed it through line 10 into vacuum flash tower 11.

The overhead from separator 7 passes through 45 line 12 into initial heat exchanger 4, which contains the heating coil 14 for the virgin feed stock, and then to a second heat exchanger 13, and then into bubble tower 15, from which gasoline and lighter hydrocarbons are taken off overhead 50 through line 16 and cycle gas oil is withdrawn from the bottom through line 17.

The initial condensate from the overhead from separator 7 is withdrawn from heat exchanger 4, through line 18 and reintroduced into the top of 55 separator to act as reflux. The condensate in heat exchanger 13 is withdrawn through line 19 and added to the cycle gas oil in line 17, the mixture being passed through coil 20 in heat exchanger 13 and thence to cracking coil 21, from 60 which the cracking products are discharged into the bottom of a soaker 22, which may be downflow as well as upflow, from which they pass to the bottom of separator 7 at a point below tray 9.

The vapors from the cracked cycle stock pass 65 upwardly through the central opening 23 in tray 9 and serve to strip the downwardly flowing liquid products from the cracked virgin stock. The tar resulting from the cracking of the cycle stock is withdrawn from separator 7, through line 24, 70 and charged into vacuum flash tower 11 at a point below the point of introduction of line 10. Between the points of introduction of the two tars are fractionating plates 25. The final tar of a gravity much below that which can be obtained without excessive coking in separator 7 is

withdrawn through line 26, and the overhead, which is composed mainly of hydrocarbons boiling within the gas oil range, is removed from tower 11 through line 27 and passed through a condenser 28 into an accumulator 29, from which it is pumped through preheater 30 and added to the feed to coil 21.

A line 31 connects line 19 with line 18 and valves 32, 33 and 34 are provided so that by suitable manipulation the condensates from either 10 or both of exchangers 4 and 13 may be sent to the top of the separator as reflux, or to line 17 as recycle stock.

A pressure reducing valve 35 is provided in line 12 at a point just before bubble tower 15 15 and in lines 10 and 24 at a point just before flash tower 11. Since the cycle stock cracking coil is often operated at a higher pressure than the virgin stock cracking coil, it is advisable to have a pressure reducing valve 36 in the line between 20 soaker 22 and separator 7, so that the pressure maintained in separator 7 can be substantially the same as that maintained in the virgin stock cracking circuit. In the event that each crack- 25 ing circuit is provided with an individual separator, there need be no reducing pressure valve between the cycle stock cracking equipment and its corresponding separator. A greater amount of preheat can be obtained from the overhead 30 from this individual separator than can be obtained from the cracked cycle stock in the arrangement shown in the drawing. The additional preheat, however, probably does not compensate for the extra equipment that would be 35 required in such an arrangement, although this arrangement is contemplated by the present invention. To provide for operation of the separator at a lower pressure than that maintained in either cracking circuit, a reducing valve 37 is 40 provided between soaker 6 and the separator.

The conditions of operation in a cracking system of the type described have been previously stated. In the preferred embodiment of the process of the present invention, as distinguished 45 from the previous operation, the pressure in the separator where a common separator is employed will be substantially the same as that in the lower pressure cracking zone. Where individual separators are employed, the pressure in 50 separator 7 will be substantially the same as the pressure in its corresponding cracking zone, the difference in pressure between the two in any case being only the drop in pressure resulting from the passage of the reaction material 55 through the equipment. In either case, pressure is maintained on the overhead products from the separator to a point just before the introduction of these products into the bubble tower, which is normally operated at a considerably lower pressure, in some cases as low as atmospheric pressure. The pressure on the vacuum flash zone is 60 ordinarily less than atmospheric, preferably about 50 mm. of mercury.

In a specific practical operation in the apparatus shown in the drawing, the temperature at the outlet of coil 5 is 840° F. and at the outlet of coil 2 is 877° F. The cracked effluent enters the separator at a temperature of about 800° F. The pressure on coil 5 and soaker 6 is about 300 70 lbs./sq. in. and on coil 21 and soaker 22 about 750 lbs./sq. in.

The separator 7 is held under a pressure of about 90 lbs./sq. in. The temperature at the bottom of the separator is about 770° F. and at the 75

outlet of tray 9 about 720° F. The temperature at the top of the separator is about 680° F. The pressure in the bubble tower is about 80 lbs./sq. in. and in flash tower 11 about 50 mms. of mercury.

The nature and objects of the present invention having been thus described and the preferred embodiment of the same having been illustrated, what is claimed as new and useful and desired to be secured by Letters Patent is:

1. In a two-circuit cracking process, in which two stocks of different degrees of refractoriness are separately cracked under pressure, the steps which comprise discharging said cracked stocks into separate separating zones maintained under superatmospheric pressure, separately collecting a tar from each of said separating zones and discharging said tars into a common vaporizing zone maintained under a lower pressure, the tar from the more refractory stock being introduced into said zone at a point below the point of introduction of the tar from the less refractory stock and the liquid constituents of the latter being impeded in their downward flow and being passed counter-currently to the vapors evolved from the former.

2. In a two-circuit cracking process, the steps which comprise subjecting a heavy stock to cracking conditions under superatmospheric pressure, subjecting a more refractory stock to more severe cracking conditions, discharging cracking products from both stocks into a common separating zone maintained under superatmospheric pressure, impeding the downward flow of the liquid constituents of the cracked less refractory stock, passing the vapors from the

cracked more refractory stock upwardly in counter-current to said liquid constituents, separately collecting a tar from the cracked less refractory stock and the cracked more refractory stock, discharging said tars at different levels into a common vaporizing zone maintained under reduced pressure, the tar from the less refractory stock being introduced into said zone at a point above the point of introduction of the tar from said more refractory stock, impeding the downward flow of the liquid constituents of the tar from the said less refractory stock and passing vapors from the tar from said more refractory stock upwardly in counter-current to said liquid constituents, withdrawing a combined tar from the bottom of said zone and withdrawing a lower boiling material from the top of said zone.

3. A process according to claim 1 in which the separate stocks are cracked under superatmospheric pressure and discharged into individual separating zones maintained under substantially the same pressure as its corresponding cracking zone, and the vapors from the separating zones are passed while still under pressure into heat exchange relation with at least one of the charging stocks.

4. A process according to claim 2 in which the feed stocks are cracked under superatmospheric pressure and the separating zone is maintained at a pressure not substantially less than that of the lower pressure cracking zone, and the vapors from the separator are passed into heat exchange relation with at least one of the charging stocks.

ALBERT C. PATTERSON.
